UNITED STATES PATENT OFFICE.

LEE R. TALBERT, OF LOS ANGELES, CALIFORNIA.

KEY LOCK.

Application filed October 12, 1922. Serial No. 593,975.

To all whom it may concern:

Be it known that I, LEE R. TALBERT, a citizen of the United States, residing at Los Angeles, in the county of Los Angeles and State of California, have invented new and useful Improvements in Key Locks, of which the following is a specification.

This invention relates to lock key retaining means, and has for its object to provide an extremely simple, cheap, practicable and substantial device for holding an ordinary bit key in its lock. Another object is to provide a key locking device that may be readily inserted through the usual aperture in the head or handle of the key and then attached to the contiguous shank of a door knob in which the lock and key are arranged.

Other objects and advantages will be made manifest in the following specification of an embodiment of the invention illustrated in the accompanying drawings, wherein

Figure 1 is a perspective of the improved device as applied.

Fig. 2 is a side elevation or plan of the detached key retainer.

The device of the present invention consists of a suitable shank 2 which may be made of wire having strands twisted upon each other to secure strength and economical construction. The ends of the wire, of which the shank is formed, are bent into sections 3-3 and are adapted to be snapped or

slipped around the stems of a door knob K, Fig. 1.

In use, after the door lock key has been turned in the lock, the shank 2 of the retainer is slipped into the aperture of the handle H of the key and then the split ring parts 3-3 of the retainer are passed around the shank of the door knob. In its arrangement and combination it will be seen that it is impossible to rotate the key in the lock since the shank of the retainer serves as a bar or stop.

The contiguous ends of the semicircles 3 may be provided with hooks 4 to be interengaged to prevent accidental dislodgment of the retainer from the stem of the door knob.

Further embodiments, modifications and changes may be resorted to within the spirit of the invention as here claimed.

What is claimed is:

A key retaining device consisting of a piece of wire strands of which are twisted one on the other to form a shank, and the ends of the wire being provided with portions to engage around the shank of a door knob and consisting of semicircular interlocking end portions.

In testimony whereof I have signed my name to this specification.

LEE R. TALBERT.
